J. E. OGDEN.
CONCRETE INSERT,
APPLICATION FILED OCT. 19, 1918.

1,351,119.

Patented Aug. 31, 1920.

Inventor
John Edward Ogden

Marshall & Dearborn

UNITED STATES PATENT OFFICE.

JOHN EDWARD OGDEN, OF CORNWALL, NEW YORK.

CONCRETE-INSERT.

1,351,119.

Specification of Letters Patent. Patented Aug. 31, 1920.

Application filed October 19, 1918. Serial No. 258,772.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Concrete-Inserts, of which the following is a specification, reference being had to the accompanying drawings, 10 forming a part thereof.

My invention relates to improvements in concrete inserts for the reception of bolts and the like, and its object is to provide a simple and inexpensive device for this purpose which is easy to install and which provides for a maximum adjustment of the position of the bolt.

In order that my invention may be thoroughly understood I will now proceed to 20 describe the same in the following specification and will then point out the novel features thereof in appended claims.

Referring to the drawings:

Figure 1 is a sectional side elevation of 25 an insert which is made according to and embodies this invention and a portion of a concrete floor in which it is embedded, together with a bolt supported by the insert.

Fig. 2 is a sectional end elevation of the 30 same parts. The section in this figure is taken on the line 2—2 of Fig. 1.

Fig. 3 is an inverted plan view of the insert and the bolt, the shank of the bolt being shown in section.

Fig. 4 is a sectional side elevation of an 35 insert of modified construction with a nut therein.

Fig. 5 is a sectional end elevation of the insert shown in Fig. 4, the section being 40 taken on the line 5—5 of Fig. 4.

Like characters of reference designate corresponding parts in all the figures.

10 designates a rectangular box-like housing open at the bottom. 11—11 are inwardly projecting flanges along the lower edges of the housing. Opposite parts of these flanges are cut off to form beveled ends 12 and 13. 14 are outwardly projecting hooks at the ends of housing and 15 are 45 other hooks projecting upwardly from the housing and facing toward each other. These hooks are provided for the purpose of

receiving the reinforcing rods 20 in the concrete body 21. From the lower edge of the housing near the center thereof, lugs 16 55 which are notched as at 17, project outwardly. The lower surfaces of these lugs are preferably slightly above the lower edges of the housing 10.

30 is a flap, pivoted to the housing by a pin 31. The free end 32 of this flap is beveled to rest upon the beveled ends 12 of the flanges 11, and another part 33 is beveled to rest upon the flanges at 13. The free end is cut away as shown at 34 to form continuations of the flanges 11.

Before more specifically describing the last two figures of the drawings, I will describe the use and operation of this device. The housing is placed upon the mold board 70 before the concrete is poured and may be fixed in desired position, by nails 37 or the like, which are driven into the mold board through the notches 17 in the lugs 16. Then the reinforcing rods 20 may be sprung under the downwardly facing hooks 14 and 15 after which the concrete is poured over the device completely embedding it but leaving the lower edges of the housing flush with the under surface of the concrete. After 80 the concrete is set and the mold board removed, the lower ends of the nails 37 may be bent up out of the way as shown at 38 (Fig. 2).

The head 41 of a bolt 40 may now be 85 pushed up into the housing through the trap formed by the pivoted flap 20. This operation will push the flap up into the position in which it is shown in broken lines at 30^A in Fig. 1, but it will immediately drop down to form a continuation of the flanges 11. The head 41 of the bolt will now rest on these flanges. If desired, a nut may be inserted instead of a bolt head.

It may be seen that the bolt is free to be 90 moved longitudinally throughout the length of the device for adjustment. The distance B (Fig. 3) between the flanges is slightly less than the distance A from one edge of the shank of the bolt to the opposite edge 100 of its head. This holds the bolt from being pulled out but permits a lateral adjustment of its position. The distance between the opposite sides of the housing is less than the

maximum transverse dimension of the bolt head so that the bolt cannot rotate when a nut is screwed onto it.

The bolt may be removed if desired by 5 moving its head off from the flap and then pushing the flap up. A nut may be removed in the same manner.

Some of the advantages of this device 10 may be attained by using the simpler form of construction shown in Figs. 4 and 5. In this case the housing 10^A has its flanges 11^A extending throughout its length and there is no flap. An opening 50 is provided in the upper part of the housing, of sufficient size 15 to permit the insertion of a nut 42. When this form of the invention is used, the nut is inserted before the concrete is poured and the opening 50 closed by a stopper 51. The nut is retained as before and after a 20 bolt is screwed into it its position may be adjusted longitudinally and laterally, but the nut cannot be removed as it can when the flap is provided.

No structural limitations are intended 25 other than those imposed by the appended claims.

What I claim is:

1. A concrete insert comprising a box-like 30 housing open on one side having parallel side walls and flanges near opposite edges of said side walls extending inwardly therefrom in a plane normal to the planes of said side walls and extending substantially throughout the length of said side walls for 35 supporting the head of a bolt or nut, a part of at least one of said flanges being inwardly movable to permit the insertion of a bolt head or nut.

2. A concrete insert comprising a box-like 40 housing open on one side having parallel side walls and inwardly extending flanges near opposite edges of said side walls throughout the length thereof for supporting the head of a bolt or nut, a part of at 45 least one of said flanges being inwardly movable out of its normal plane to permit the insertion of a bolt head or nut.

3. A concrete insert comprising a box-like 50 housing open on one side having inwardly extending flanges near opposite edges of its open side and shorter than said side for supporting the head of a bolt or nut, and a flap at the ends of the flanges pivotally connected with the housing.

55 4. A concrete insert comprising a box-like housing open on one side having inwardly 60 extending flanges near opposite edges of its open side for supporting the head of a bolt or a nut, and a flap pivotally connected with the housing, parts of said flap forming in one position of the flap, continuations of said flanges.

5. A concrete insert comprising a box-like 65 housing open on one side having inwardly

extending flanges near opposite edges of its open side for supporting the head of a bolt or nut, and a flap pivotally connected with the housing, parts of said flap forming in one position of the flap, continuations of said flanges, the free end of the flap being 70 arranged to rest upon the ends of the flanges.

6. A concrete insert comprising a box-like 75 housing open on one side having inwardly extending flanges near opposite edges of its open side for supporting the head of a bolt, the ends of said flanges being beveled, and a flap pivotally connected with the housing having beveled portions at its free end and arranged to rest upon the beveled ends of 80 the flanges and parts of said flap forming in one position of the flap, continuations of said flanges.

7. A concrete insert comprising a box-like 85 housing open on one side having inwardly extending flanges near opposite edges of its open side for supporting the head of a bolt, opposite portions of said flanges being cut away to form oppositely beveled ends, and a flap transversely pivoted to the housing 90 adapted in one position to rest upon the beveled ends of the flanges and to form continuations thereof.

8. A concrete insert comprising a housing 95 having an open side, a pivotally supported flap arranged to partially close the open side and to be moved in one direction about its support to permit the insertion of the head or nut of a bolt, and means for preventing movement of the flap about its support in 100 the opposite direction beyond its side closing position.

9. A concrete insert comprising a housing 105 having an open side, a flap pivoted near one of its ends to said housing near one end of the housing, arranged to partially close the open side and to be moved in one direction about its pivot to permit the insertion of the head or nut of a bolt, and means for preventing movement of the flap about its pivot 110 in the opposite direction beyond its side closing position.

10. A concrete insert comprising a housing 115 having an open side, a flap pivoted to said housing arranged to partially close the open side and to be moved in one direction about its pivot to permit the insertion of the head or nut of a bolt, and means for preventing movement of the flap about its pivot in the opposite direction beyond its side 120 closing position, said flap being constructed to form in its side remote from its pivot a recess of less width than the smallest transverse dimension of the head or nut of the bolt.

11. A concrete insert comprising a housing 125 having an open side, a flap pivoted near one of its ends to said housing near one end

of the housing, arranged to partially close the open side and to be moved in one direction about its pivot to permit the insertion of the head or nut of a bolt, and means for preventing movement of the flap about its pivot in the opposite direction beyond its side closing position, said flap being con-

structed to form in its side remote from its pivot a recess of less width than the smallest transverse dimension of the head or nut of 10 the bolt.

In witness whereof I have hereunto set my hand this 16th day of October, 1918.

J. EDWARD OGDEN.
